G. H. Baker
ATTORNEY

UNITED STATES PATENT OFFICE.

FRANCIS J. DOWLING, OF NEW YORK, N. Y.

SPRING CLAMP MECHANISM.

Application filed November 30, 1923. Serial No. 677,623.

To all whom it may concern:

Be it known that I, FRANCIS J. DOWLING, a citizen of the United States, residing at New York city, borough of Manhattan, in the county of New York and State of New York, have invented certain new and useful Improvements in Spring Clamp Mechanism, of which the following is a specification.

10 This invention relates to spring clamp mechanism, an object of the invention being to provide such a device which will securely clamp the arm or other portion of the body and securely hold a flash light so as to throw 15 the light on the work, especially when the work is normally in the shadow or awkward place.

15 A further object is to provide a device of the character stated which will securely hold a flash light of round, oval, or other cross sectional shape and which can be easily and quickly operated to clamp the light and the portion of the body desired.

20 A further object of the invention is to provide a device of the character stated in which the light can be moved and secured at the desired angle or position of adjustment so as to throw the light exactly where desired.

25 Another object is to provide, as an article of manufacture, a clamp device embodying a plurality of clamps, each for holding articles of various sizes, and including means for the manipulation of either clamp 30 whether or not the other clamp is occupied.

35 With these and other objects in view the invention consists in certain novel features of construction and combinations and arrangements of parts as will be more fully 40 hereinafter described and pointed out in the claims.

In the accompanying drawings:—

Fig. 1 is a view in elevation of a preferred embodiment of the invention.

45 Fig. 2 is a side elevation of the same.

Fig. 3 is a front elevation of a modification.

Fig. 4 is a side elevation of the same.

I would have it understood that for brevity I shall hereinafter refer to the device as being positioned on the arm of the user, but it is to be understood that it may be positioned on the leg or other portion of the body or any other convenient support 50 with equal convenience.

The preferred embodiment of my invention shown in Figs. 1 and 2 comprises a single strip of spring metal bent midway its ends into general circular form to provide an article holder 46, the latter having 55 an offset or recess 47 therein to accommodate or permit movement therethrough of the switch of the flash light.

The ends of the strip are crossed at the base of the holder 46 and project laterally 60 and each end of the strip is given two opposite bends or extensions as shown at 49 and 50 with a straight portion 51 between them, the straight portions 51 of the respective strip ends crossing each other at an 65 angle as clearly shown in Figure 1.

These portions of the strip ends forming the bends 49, 50 and the crossed portions 51 as well as the portions of strip adjacent thereto are preferably made narrower than 70 the other portions of the strip as indicated in Figure 2, so as to prevent distortion of the extremities of the strip which form the body clamp 52.

The members of the body clamp 52 are 75 bowed outward and their ends are normally spaced from but adjacent to each other.

In operating this form of device the body clamp 52 is compressed, as indicated by the 80 dot and dash lines, which causes the holder 46 to expand as also indicated by similar lines. When in this position the article can be easily inserted in the holder and will be 85 securely clamped when pressure on the body 90 clamp 52 is released. To expand the body clamp 52 so as to readily position the same, inward pressure is applied against the outside of the arms of the clamp 46 or the 95 bends 50, preferably the latter when the parts will assume the position shown in dotted lines.

To indicate the points of pressure and the direction of movement I have employed the reference characters "a" with arrows pointing toward the body clamp members to show the first operation above described and the reference characters "b" and arrows to indicate the second operation described. Or instead of applying outside pressure to the 100 clamp mechanisms, the operator may, if desired, apply pressure upon the inner surfaces of the members or jaws of either clamp, causing the same to separate or spread, and when this is done the jaws of 105 110

the other clamp will approach each other or contact if unoccupied, or if occupied, the article gripped thereby will be gripped with an additional force in proportion to the expanding force applied upon the inside as just stated.

Figures 3 and 4 are views in elevation at right angles to each other illustrating another modification.

10 In this modification a single strip of metal is employed with the intermediate portion thereof bent into general circular form to provide a loop or flash light or other article holder 53 with its offset portion 54. The 15 ends of the strip are crossed at the base of the holder 53, as indicated at 55 and the extremities of the strip are bowed outward to form the body clamp members 56.

20 The ends of the members 56 are normally sufficiently close together as indicated so that pressure on the members 56 will expand the holder 53, and pressure on the latter will expand the body clamp, when the holder 53 is not occupied. When, however, 25 the lamp is in place the operator, to spread the legs 56, has merely to grasp around the lamp and bear with his fingers against the inner sides of the legs, applying force thereto in opposite directions. Or if the legs 30 were made one longer than the other as above described, the clamp would be applied as stated in connection with the first figures.

35 It will thus be noted that in all forms of my improved device I provide flash light holding means and body clamping means which are capable of a wide range of adjustment to accommodate themselves to all ordinary conditions and which insures the proper holding of the light to illuminate the 40 work.

Furthermore it will be noted that the devices can be operated with one hand which is important and in many cases absolutely necessary.

45 Various other changes might be made in the general form and arrangement of parts described, without departing from my invention, and hence I do not limit myself to the precise details set forth but consider myself at liberty to make such changes and alterations as fairly fall within the spirit and scope of the appended claims.

50 It will be observed also that in all forms the body holding clamp and the article holding clamp are both well adapted for the accommodation of various sizes of articles clamped. That is to say, the body holder will be applicable to either an arm or leg or other part of the operator or mechanic and the flash light holding clamp in each case is adapted for holding all standard makes or sizes or shapes of lamp bodies or other articles.

55 It will be noted also that each clamp portion of the device is both expansible for the

reception of various sizes, forms, or shapes of objects or articles and also is automatically contractible for gripping the articles or objects so received. The longer arm or leg of the body clamp may be engaged 70 against the portion of the body to be embraced by such clamp while the hand of the operator grasping the device as a whole or the shorter leg, with or without the flash light or article being held in place, by the 75 use of a moderate degree of force, the two free ends of the body clamp will be sufficiently spaced or moved relatively to admit freely the portion of the body intended for the clamp. Again, as above premised, in the 80 principal forms of the invention, compression applied to the top or shoulder portions of the body clamp will cause or tend to cause the expansion or enlargement of the 85 opening of the flash light or other article holding clamp carried thereby.

I claim:

1. The herein described clamp mechanism comprising a pair of clamps located end to end and in substantially the same plane, each clamp having arms at the sides thereof, the diagonally opposite arms of both clamps consisting of unitary structures movable relatively to each other and crossing each other so that when either clamp is compressed the other is opened, said structures having extending portions between the clamps comprising loops crossing each other. 90

2. As a new article of manufacture, clamp- 100 ing mechanism comprising a plurality of spring clamps associated with each other, each of the clamps being capable of a wide range of manipulation for gripping and holding articles of various sizes and so constructed that pressure applied to the inner side of either of the clamps, when the clamps are in normal position, will cause the other clamp to contract for holding purposes, and additional means to cause over expansion of one of the clamps for the release or 110 reception of the aforesaid article while the other of the clamps is occupied, and each of the clamps, furthermore, being capable of holding articles when contracted beyond normal position with a force proportional to the over expansion of the other clamp. 115

3. The herein described combined clamp mechanism comprising a plurality of spaced expansible clamps capable of being used for holding purposes simultaneously, and auxiliary actuating means for the clamps adapted to open either of them when actuated by the hand of the operator, said actuating means comprising extensions adjacent to each of the clamps upon which the operator may exert pressure for the purpose of opening said clamps. 120

4. In a clamp mechanism, the combination of a plurality of clamps whose normal holding position is contracted for holding 130

purposes, each of the aforesaid clamps being capable of contraction to expand the other clamp, and independent means at the end of one of the clamps to expand one of the clamps even though the other clamp is occupied.

5. The herein described combined clamp mechanism comprising a plurality of spaced expandible clamps capable of being used for holding purposes simultaneously, and auxiliary actuating means joining said clamps and operative to cause expansion of either of the clamps while the other is occupied, one of said clamps being movable at each end 10 thereof for the purpose of expansion as aforesaid, said clamp being provided for this purpose with an extension at the free end thereof, said clamp being operative by the actuating means at its other end, thus rendering said clamp expandible at either end 15 of the same.

6. The herein described combined clamp mechanism comprising a plurality of spaced expandible clamps capable of being used for holding purposes simultaneously, one of 20 said clamps having a pair of legs one of which is longer than the other to facilitate the opening of said clamp, and flexible auxiliary means joining said clamps and 25 capable of taking up part of the flexure upon

the clamp having the longer leg when the same is opened as aforesaid.

7. As a new article of manufacture, clamp mechanism comprising a plurality of spaced clamps each of which is capable of manipulation for holding articles of various sizes, and so constructed that pressure applied to the inner side of either of the clamps when said clamps are in normal position will cause the contraction of the other clamp, while pressure applied upon the outside of either of the clamps while said clamps are in normal position will cause the expansion of the other clamp, each of the clamps being capable of holding articles of various sizes when contracted to or toward or even beyond 40 normal position.

8. In a device of the character set forth, a plurality of spring clamps associated with one another, each of the aforesaid clamps 45 being capable of clamping and holding firmly articles of various sizes, pressure applied to either of the clamps providing for the expansion of the other clamp for the reception or release of the aforesaid articles, and additional means to provide for the expansion of one of the clamps when the other clamp is occupied.

In testimony whereof I affix my signature.
FRANCIS J. DOWLING.
